UNITED STATES PATENT OFFICE

CARLOS E. DAUSSA, OF NEW YORK, N. Y.

INSULATOR

Application filed June 9, 1930. Serial No. 460,047.

My invention relates to improvements in insulators wherein an insulating body is arranged to receive and normally enclose a card identifying a conductor connected thereto with respect to a remote connection connected to said conductor.

My invention is particularly useful in connection with outside aerials for radio reception wherein a plurality of aerials are separately connected to different apartments within a building, whereby each aerial may be effectually identified with respect to the particular apartment to which it is connected.

15 The primary object of my invention is to provide an improved insulator having means for identifying conductors attached thereto.

Another object is to provide an improved insulator wherein an identifying card may be 20 detachably mounted upon the insulator to indicate the relation or location of conductors connected thereto.

A further object is to provide an improved 25 device of the character described slotted to receive and normally enclose an identifying card.

A still further object is to provide an improved device which will effectually protect 30 the indicia bearing portion of an identifying card from exposure, and in which the card may be readily removed for inspection or replacement when desired.

Another object is to provide an improved 35 identifying insulator of transparent character arranged to enclose an identifying card whereby conductors connected to the insulator may be identified by inspection through the transparent walls of the insulator.

I accomplish these and other objects by 40 means of the improved device disclosed in the drawing forming a part of the present application, like characters of reference being used to designate similar parts throughout the specification and drawing. In the 45 drawing,

Fig. 1 is a side elevation of my improved insulator with an identifying card mounted thereon;

50 Fig. 2 is a top view of the device as shown in Fig. 1; and

Fig. 3 is a transverse vertical midsectional view of the insulator and identifying card.

Referring to the drawing, the numeral 1 is used to designate the body portion of an insulator, formed from suitable insulating material, preferably transparent glass. The body 1 is preferably substantially cylindrical in form and provided with annular flanges 2 and apertured knobs 3 at each end thereof whereby the insulator may be mounted in the ordinary and well known manner.

55 The body 1 is provided with a longitudinally disposed recess 4 opening outwardly through one side of the body and extending diametrically into the body to a desired depth. The outer open end of the recess 4 is enlarged, as at 5, the enlarged portion preferably having diverging side walls and forming shoulders 6 spaced inwardly from the surface of the body. The recess 4 is made of a length and depth sufficient to accommodate card 7 having suitable characters 8 identifying the insulator and conductors connected thereto.

60 A block 9 is shaped to fit within the enlarged portion 5 of the recess 4 and to seat therein upon the diverging walls and the shoulders 6. The inner face of the block 9 is grooved to engage the outer edge of the card 7, and a slot 10 is formed through the block, preferably at the center thereof, to receive an outwardly disposed extension or tab 11 carried by the card 7 whereby the card and block may be removed from the insulator when desired. The block is formed of any suitable material such as rubber, cork, wood, or the like adapted to be pressed firmly into the recess 4 to exclude moisture from the recess 4 and protect the card 7 from exposure 65 to the elements.

70 My improved insulator is particularly designed for use in connection with outside aerials of apartment houses and the like wherein numerous outside aerials are individually connected to outlets situated in the several apartments of a building. In many cases, such outside aerials are not adequately marked to identify the particular apartments to which they extend, and much inconvenience frequently results from the necessity of 75 80 85 90 95 100

testing to determine which of a number of aerials is connected into a particular apartment. In this connection, my improved device is connected in the ordinary and well known manner, and the card 7 is marked with the name of the owner and the apartment number to which the aerial is connected. In installing or servicing radios, the service man may determine which of a number of aerials is the one desired by merely glancing at the name and apartment number through the transparent body of the insulator, or in case the insulator is constructed from nontransparent material, by lifting the card outwardly from the recess 4 by means of the extension 11.

While I have illustrated and described my invention only in one embodiment and as applied in connection with radio aerials, the device is of course subject to modification in various ways for use in other connections, and to meet other requirements. I therefore do not wish to be restricted to the specific form and arrangement illustrated, but desire to avail myself of all modifications which may fall within the scope of the appended claims.

Having thus described my invention, what I claim is:

30 1. An insulator comprising a body formed from insulating material and having means to engage a conductor connected thereto; and an identifying member detachably mounted within the body for identifying the conductor, and provided with an outwardly extending means for removing the member from the body.

40 2. An insulator comprising a body formed from insulating material and having means to engage a conductor connected thereto, said body having a recess formed longitudinally therein; and a card insertable into the recess and having identifying indicia thereon to identify the conductor, said card having an outwardly extending tab for removing the card from the recess.

50 3. An insulator comprising a body formed from insulating material and having means to engage a conductor connected thereto, said body having a recess formed longitudinally therein intermediate the ends thereof; a block removably fitted into an enlarged outer portion of the recess; and a card detachably secured to the block and insertable into the recess, said card having identifying indicia thereon to identify the conductor and being provided with a tab extending outwardly through the block for removing the block and card from the recess.

60 4. An insulator comprising a transparent body provided with conductor receiving means at its opposite ends, said body having a recess formed therein; and an identifying member insertable into the recess and having

identifying indicia thereon observable through the insulator body.

5. An insulator comprising a transparent body provided with apertured conductor receiving portions at its opposite ends; said body having a recess formed therein; and an identifying member removably insertable into the recess and having identifying indicia thereon observable through the insulator body.

6. An insulator comprising a transparent body provided with conductor receiving means at its opposite ends, said body having a recess formed therein; a card removably insertable into the inner portion of the recess, said card having identifying indicia thereon; and a block engaging the card and seating in the outer portion of the recess.

In witness whereof I hereunto set my signature.

CARLOS E. DAUSSA.
